UNITED STATES PATENT OFFICE.

EUGENE B. WALSH, OF BROOKLYN, NEW YORK, ASSIGNEE, BY DIRECT AND MESNE ASSIGNMENTS, TO THE WALSH MANUFACTURING AND HEATING COMPANY, INC., A CORPORATION OF NEW YORK.

RADIATOR-HEATER.

1,232,131.

Specification of Letters Patent.

Patented July 3, 1917.

Application filed January 5, 1915. Serial No. 591.

To all whom it may concern:

Be it known that I, EUGENE B. WALSH, a citizen of the United States, and a resident of the borough of Brooklyn, city of New York, county of Kings, and State of New York, have invented certain new and useful Improvements in Radiator-Heaters, of which the following is a specification.

The present invention relates to radiator heaters. One object of the invention is to provide a separately constructed heating attachment for heating radiators, which may be attached to or used in conjunction with a radiator which is otherwise complete. The present device is adapted to be attached to the ordinary forms of radiators now in general use without any special construction or reconstruction of the radiator. Thus it is possible to use a common form of radiator in conjunction with the heater to provide a complete heating unit. Or, it is possible to attach the present device to one or more radiators which already form part of a heating system having a number of heating units, whereby the separate unit may be independently used for heating when the system as a whole is not in operation or where the system as a whole is not providing as much heat as is desired from the particular unit referred to.

A further object of the invention is to provide a radiator heater having a novel form of base or receiving compartment, for the radiator, which will so inclose part of the latter as to produce a maximum quantity of heat with a minimum consumption of fuel by permitting the proper portions of the radiator sections to be inclosed or subjected to the action of the flame to obtain the best results.

Another object of my invention is to provide a heater which may be so combined with an ordinary radiator as will provide a compact and not unsightly combination. Another object thereof is to provide a heater having the above characteristics and which may be very easily attached to or detached from a radiator with the least skill and labor.

Another object of my invention is to provide a heater which may be very easily made in any size or length to accommodate a ra-

diator of desired size or having any desired number of sections.

In the drawings forming part of this application,

Fig. 1, is a plan view of a heater embodying my invention, attached to an ordinary radiator,

Fig. 2, is a front elevation thereof, partly broken away substantially on the line 2—2 of Fig. 1,

Fig. 3, is a sectional view, taken on the line 3—3 of Fig. 2, and

Fig. 4, is a sectional view, taken on the line 4—4 of Fig. 3.

Fig. 5 is a detailed view of one end of the radiator and heater, showing how the radiator may be connected with a regular steam heating system.

It will be understood that the form of the radiator and the number of sections may vary; but I have illustrated my invention attached to a radiator of common form, having six sections.

I have shown a radiator 1, which comprises a series of sections 2 and it may be connected with an ordinary steam or hot water system by means of the usual pipe 13^a or this end of the radiator may be blocked 80 and the radiator used as an independent unit. The radiator has the usual legs 4 at the several corners thereof and the several sections are connected to be in communication with each other by the usual connections 5.

The device comprising the invention consists of a base or compartment 7, which is preferably of a portable and detachable nature and of rectangular shape. This compartment is preferably formed of end members 8, 9 each having two legs 10, and preferably made as a casting, and the plates 11, 12, extending between the end plates and at their ends secured thereto, as by means of 95 the screws 13. The plate 12 constitutes the rear wall of the combustion compartment 14, and from the top thereof extend the projecting plates 15. These latter extend forward and between the several sections 2 of 100 the radiator and coöperate with similar plates projecting from the front wall, to form the top closure for the combustion chamber. The number and disposition of

these laterally extending plates 15 will depend upon the number and disposition of the several spaces 16 between the sections of the radiator. In practice radiator sections are generally made to measure a definite and standard distance between their centers, so that the spaces 16 between the sections will vary in number rather than otherwise, according to the number of sections of which the different radiators are composed. Since the front and rear walls are separate from the end walls 8, 9 they may be made of sheet metal of considerable length and then cut into various lengths to suit radiators having different numbers of sections. This facilitates the application of the invention to radiators at present in use.

The front wall 11, is similar to the rear wall and it is attached to the end walls in a similar manner. It has plates 17 extending rearward over the bosses 5 at the lower ends of the radiator sections, similar to and preferably slightly overlapping the plates 15.

The plates 15 and 17 constitute the top of the combustion chamber and they prevent the escape of the heat therefrom immediately; but, since there must be some escape for the heat which is continually generated the plates 15, 17 are preferably so made as to only partially close the spaces 16, between the radiator sections, thus leaving spaces 18 which will permit the heat to escape upwardly and along the radiator sections, whereby the heat will be utilized to the fullest extent.

The radiator is partially received in the combustion chamber, that is, the lower ends of the sections 2 and the connections 5 are inserted in the combustion chamber and the legs 4 of the radiator are received on the tops of the legs 10 of the heater, inside the end and side walls. Thus the radiator is supported by the heater a slightly greater distance above the floor than ordinarily.

There is a pipe 19 extending through an aperture 20 in each end wall and it is capped at one end, 21.

This pipe has apertures 22 along the top and it serves as a burner for whatever fuel is to be used for heating such, for instance, as gas. This pipe 19, is arranged below the connections 5 and under the sections 2 and between the legs of the radiator, and in this position it is adapted to heat the water or steam in the sections and in the connections 5.

The bottom of the combustion chamber is preferably double and so arranged as to admit an ample supply of air for combustion and also prevent the heat from radiating downwardly from the burner to the floor. For this purpose I have provided a bottom plate 23, which rests upon the legs 10 and is supported thereby. This plate has slots or openings 24 extending a substantial part

of its length and at each side of the burner 19, to permit air to enter the combustion chamber to facilitate combustion. The plate 23, is bent upwardly to form baffles 23^a at the inner edges of the openings 24. These 70 baffles prevent the air which enters the openings 24 from blowing out the flame of the burner when it is turned low.

The bottom is also composed of a plate 25 which has its opposite sides turned up at 75 26 and then inwardly at 27 so as to rest upon the side edges of the plate 23 and thus support the plate 25 on the plate 23 and in spaced relation thereto. The space 28 between the plates 23 and 25 is open at both 80 ends of the latter. The air enters at these open ends, travels more or less along the space 26 and passes upwardly through the openings 24 into the combustion chamber.

There is thus a continuous supply of air 85 from below. Owing to the double bottom and the passage of the cooler air through the space 28 the heat in the combustion chamber can not injuriously affect the floor.

There is preferably provided a door 29 in 90 the front wall, having a handle 30, to provide access when lighting the burner.

The above parts constitute the heating portions of the device.

The numeral 31 indicates any form of 95 thermostatic or pressure valve which is connected to the pipe section 6, to communicate with the interior of the radiator sections, and it is adapted to coöperate with a valve 32 interposed in the supply pipe 33. The 100 pipe 34 connects with the supply pipe 33 and leads to a mixing chamber 35 communicating with the burner 19. The supply of fuel through the pipe 33 and into the mixing chamber 35 is regulated by a valve 40 105 which is preferably of the needle type. The casing of the diaphragm or other valve communicates with the pipe section 6, so that the radiator if not connected to a water supply system may be supplied through an opening 110 by unscrewing and removing the plug 37. A glass gage 38 also communicates with the upper and lower portions of the diaphragm casing for the purpose of indicating the height of the water in the radiator.

Any kind of fluid may be used for fuel, common illuminating gas being well adapted for the purpose.

In Figs. 1 to 4 I have shown the device combined with a radiator which is independent of any general heating system, but it may, if desired, be applied to a radiator which forms one of the units of a heating system. In that case it will be possible to heat the single unit or radiator when the 120 system as a whole is not, for any reason, capable of meeting the requirements. In such use of the device the heater will be constructed and applied as herein described, except that the end wall 8 will be constructed like 130

the end wall 9, as shown in Fig. 5. That is, it will have an opening 39 through which a pipe 13^a, which is connected with the heating system, may be passed and be connected 5 with one of the connections 5.

The operation of the device will be understood from the foregoing description. When the valve 40 is opened to admit gas from the supply pipe 33 it will enter the extension 41

10 where it is controlled by the thermostat and it will then pass through the pipe 34, the mixing chamber 35 and burner 19, and combustion will take place above each of the holes 22. The heat generated in the chamber 14 will effectually heat the water in the lower portion of the radiator and a portion thereof will be generated into steam which will circulate through the radiator 15 sections and the heat will radiate from the latter into the room. There is no escape for the water or steam so that there will be no rapid loss of water, and the radiator will need to be supplied with water only at long intervals.

20 It will be noted that the ordinary form of radiator may be used without modification. Since the radiator legs 4 rest upon the legs 10 which carry the weight of the radiator the construction of the heater as 25 a whole may be light and inexpensive. There need be no permanent connection between the radiator and heater, so that the latter may be removed, leaving the former intact.

30 Having described my invention, what I claim is:

1. A portable heater of the class described, comprising a casing of substantially rectilinear contour having open top and bottom portions, means at the top portion of the casing to form a tight joint with a water-carrying element mounted in the casing, feet for the element near the ends thereof to sustain the weight of the element, flanges attached to the ends of the casing and carrying said feet, a main bottom supported upon said flanges between the element and the flanges, said bottom having upturned portions producing draft openings, an auxiliary bottom in spaced relation beneath said main bottom to provide an air space and having upbent sides, the ends of said space being open to permit the circulation of air therethrough and a heating medium carried by 45 the casing between said draft openings.

50 2. A heater for radiators, comprising a casing having side and end walls adapted to receive therein the lower portion of a radiator, a lower and an upper bottom plate 55 for said casing spaced apart to form an air space open at the ends, said upper bottom plate having openings to admit air into said casing and communicating with said air space between the bottom plates, and a burner beneath the radiator and above said

bottom plates for supplying heat to the radiator.

3. A portable heater of the class described, comprising a casing having open top and bottom portions, means at the top of the casing extending inwardly to close the space between the sections of a radiator mounted in the casing, feet for the casing near the ends thereof to sustain the casing and radiator, flanges attached to the ends of the casing to support the feet of the radiator, a main bottom supported upon said flanges, said bottom having up-turned portions producing draft openings, a burner above said upturned side portions and an auxiliary bottom suspended from said main bottom in spaced relation thereto.

4. A portable heater of the class described, comprising a casing of substantially rectilinear contour having open top and bottom 85 portions, means at the top portion of the casing to close the space between the sections of a water-carrying element mounted in the casing, feet for the casing near the ends thereof to sustain the weight of the element, 90 flanges attached to the ends of the casing and carrying said feet, a main bottom supported upon said flanges between the element and the flanges, said bottom having up-turned portions producing draft openings and regulators therefor, an auxiliary bottom in spaced relation beneath said main bottom to provide an air space and having upbent sides closing said space adjacent to the draft openings, the ends of said space being open to permit the circulation of air 95 therethrough, independently of the draft openings aforesaid, and a heating medium carried by the casing between said draft openings.

5. The combination with a radiator, comprising a series of spaced sections and connecting means for said sections, said radiator having supporting legs; of a casing snugly fitting around the lower portion of the radiator and removably connected to said section-connecting means, means for supplying water to the radiator sections, a series of spaced extensions at the sides of the casing disposed between said sections, said sides 105 having inturned flanges at their lower edges, inwardly extending supports at the ends of said casing upon which the radiator legs rest, a burner extending through the casing and supported in the ends thereof beneath 110 the radiator, and a double bottom supported upon the flanges and inwardly extending supports at the bottom of the casing, said bottom having draft openings at the sides 115 for supplying air to the combustion chamber beneath the radiator, and openings at the ends for supplying air between the portions of the double bottom beneath said combustion chamber.

6. A portable heater of the class described,

comprising a casing of substantially rectilinear contour, having open top and bottom portions, means at the top portion of the casing to form a tight joint with a water-carrying element mounted in the casing, feet for the casing near the ends thereof to sustain the weight of the element, means above the feet to sustain and carry the radiator, and a

bottom for the casing having side draft openings.

Signed at the city, county and State of New York, this 22nd day of December, 1914.
